(57) **CLAIM**

The ornamental design for a plasma arc torch tip, as shown and described.

DESCRIPTION

FIG. 1 is a perspective view of the plasma arc torch tip from the top;

FIG. 2 is a perspective view thereof from below, wherein the dashed lines indicate changes in surface contour;

FIG. 3 is a perspective view thereof from above and rotated from FIG. 1;

FIG. 4 is a side elevation view thereof;

FIG. 5 is a side elevation view thereof, rotated 90° from FIG. 4;

FIG. 6 is a top plan view thereof, wherein the dashed lines indicate changes in surface contour; and,

FIG. 7 is a bottom plan view thereof.
